UNITED STATES PATENT OFFICE.

DONALD LA RUE EASTMAN, OF OLEAN, NEW YORK.

FOUNTAIN PEN.

Application filed October 25, 1921. Serial No. 510,240.

To all whom it may concern:

Be it known that I, DONALD L. EASTMAN, a citizen of the United States, and a resident of Olean, in the county of Cattaraugus and 5 State of New York, have invented a new and Improved Fountain Pen, of which the following is a full, clear, and exact description.

This invention relates to improvements in fountain pens, an object of the invention being to provide a self filling pen which comprises a minimum number of parts, and which will hold a relatively large amount of ink.

15 A further object is to provide a novel form of self filling device and to provide a pen which will be simple and practical in construction, durable and efficient in use, attractive in appearance, easy to clean, and 20 inexpensive to manufacture.

With these and other objects in view, the invention consists in certain novel features of construction and combinations and arrangements of parts as will be more fully 25 hereinafter described and pointed out in the claims.

In the accompanying drawings:

Figure 1 is a view in section through my improved pen showing the plunger in position to expel the ink from the font;

Figure 2 is a similar view showing the pen filled; and

Figure 3 is a view in transverse section on the line 3—3 of Figure 1.

35 Referring in detail to the drawings, 1 represents the barrel or font of my improved pen. The font is screw threaded at its lower end, as indicated at 2, and a screw threaded pen carrying plug 3 is screwed into the lower 40 end of the barrel in the usual manner.

45 4 represents a plunger movable longitudinally of the barrel and frictionally fitting within the same. This plunger is hollow and formed with a closed lower end 5 which serves as a plunger head. The barrel 1 telescopes between the plunger and a sleeve 6 located on the outside of the barrel and integrally connected at its upper end to the plunger, as indicated at 7. The barrel 1 is 50 externally screw threaded adjacent its upper end, as seen at 8, and the lower end of the sleeve 6 is also screw threaded at 9 to engage with the upper screw threaded end of the barrel.

55 The open upper end of the plunger 4 is closed by a plug 10. It will be seen that

the plunger forms a convenient compartment for the storage of small articles. The plug 10 which closes this compartment carries a ring 11 or other suitable device for 60 conveniently attaching the pen to a watch chain.

The operation of the device of the device is as follows: The sleeve 6 ordinarily has screw threaded engagement with the barrel 1, as 65 seen in Figure 2. When the ink has run low in the barrel, the sleeve is screwed down on the barrel until the threads 8 and 9 are out of engagement. The plunger and sleeve are then forced downwardly, as seen in Figure 1, 70 expelling any remaining ink from the pen. The lower end of the pen is inserted in an ink well or ink container and the plunger and sleeve are pulled back toward their normal position, sucking ink into the barrel. 75 The sleeve is again turned until the screw threads 8 and 9 engage and the pen is ready for use. In cleaning the pen, the plunger and sleeve may be disengaged entirely from the barrel.

80 It will readily be seen from the foregoing description that I provide a pen which is extremely practical in construction and efficient in operation. Various slight changes and alterations might be made in the general 85 form and arrangement of the parts described without departing from the spirit of the invention and hence I do not wish to limit myself to the precise details set forth, but shall consider myself at liberty to make 90 such slight changes and alterations as fairly fall within the spirit and scope of the appended claims.

I claim:

1. In a fountain pen, a barrel having an 95 open upper end, an elongated cylindrical plunger movable in the barrel through the open end thereof, a sleeve secured to the upper end of the plunger and surrounding and spaced from the same and between which and 100 the plunger the barrel is adapted to telescope with the plunger tightly fitting the barrel throughout its length, and means for removably securing the lower end of the sleeve to the upper end of the barrel. 105

2. In a fountain pen, a barrel, a plunger in the barrel, a sleeve on the outside of the barrel integrally connected to the plunger, said plunger consisting of an elongated hollow body forming a receptacle between which and the sleeve, the barrel telescopes, said receptacle being closed at its 110

lower end and open at its upper end, and a plug normally closing the open end of the receptacle.

3. In a fountain pen, a barrel having an open and externally screw-threaded upper end, an elongated cylindrical plunger movable in the barrel through the open end thereof, and a sleeve secured to the upper end of the plunger and surrounding

and spaced from the same, and between which and the plunger the barrel is adapted to telescope with the plunger tightly fitting the barrel throughout its length, the lower end of the sleeve being internally screw-threaded to engage the screw threaded end of the barrel.

DONALD LA RUE EASTMAN.
